HIGH-FIDELITY SOUND REPRODUCING APPARATUS AND METHOD OF IMPROVING THE FIDELITY THEREOF

Harold A. Wheeler, Great Neck, Vernon E. Whitman, Flushing, and Nelson P. Case and William O. Swinyard, Bayside, N. Y., assignors to Hazeltine Corporation, a corporation of Delaware

Application April 4, 1935, Serial No. 14,600

17 Claims. (Cl. 181—31)

Our invention relates to sound-reproducing apparatus and, while it is of general application, it is particularly suitable for use in connection with radio broadcast receivers.

5 In the satisfactory reproduction of sound, as from a radio broadcast receiver, two distinct problems arise. One is that of the fidelity of reproduction, that is, the uniform and distortionless reproduction of sound throughout the audible 10 frequency range. Among the important factors present to a greater or lesser extent in the sound-reproducing devices of the prior art tending to impair the fidelity of sound reproduction, might be mentioned the non-uniform frequency-response 15 characteristic of the primary sound-reproducing element; the resonant or non-uniform frequency characteristic of the housing or cabinet in which such a device is usually mounted; and interference patterns set up by waves generated by different portions of the sound-reproducing device.

A second important problem is that of the effectiveness of the device and the closely related problem of the distribution of the sound waves in 20 their projection from the device to the audience, usually involving the distribution over a room or auditorium. Among the important factors disadvantageously affecting many arrangements of the prior art in this respect may be mentioned the 25 lack of proper direction of the sound waves from the device into the room; the reflection of the sound waves from the walls, floor and ceiling, giving rise to interference patterns; and the non-uniform angular, and improper vertical distribution 30 of the sound waves as they are projected into the room, resulting in dead spots, that is, areas of very low sound intensity, accompanied by other areas of abnormally high intensity.

It is an object of our invention to provide a 35 sound-reproducing device in which the shortcomings of the arrangements of the prior art, discussed above, are largely eliminated or substantially reduced and which will reproduce sound waves with a maximum fidelity and effectiveness.

More specifically, it is an object of our invention to provide a high-fidelity sound-reproducing device having an approximately uniform frequency-response characteristic over the audio-frequency range and in which any resultant or residual non-uniformity in the frequency-response characteristic is neutralized or compensated for externally to the sound-reproducing device, per se, preferably in the electrical network to which the device is connected.

In accordance with our invention there is provided a high-fidelity sound-reproducing apparatus comprising a casing including a sound cavity shaped to conform substantially to the vertex of a trihedral angle, such as a corner of a room. 5 Within the casing is mounted a large-diaphragm type of sound-reproducing device disposed to discharge, preferably vertically, into the sound cavity at a point displaced from the vertex. The sound cavity includes means for directing or deflecting the sound waves generated by the device outwardly from the vertex with a substantially uniform angular distribution and a proper vertical distribution, as determined by the physical relationship of the sound-reproducing device to 10 an audience.

More specifically, in accordance with our invention there is provided a high-fidelity sound-reproducing apparatus comprising a casing terminating in a sound cavity shaped to conform 20 substantially to the corner of a room so that the walls and floor or ceiling constitute effectively a continuation of the walls of the sound cavity. A partition separates the cavity from the rest of the casing and a large-diaphragm type sound-reproducing device is disposed in an opening in the partition to discharge vertically into the cavity. 25 A conical deflector is positioned between the sound-reproducing device and the opening of the sound cavity and is effective to direct outwardly 30 from the vertex the sound waves generated by the device. One or more additional segmental conical deflectors and a plurality of vertical fins radiating from a point of the interior of the cavity substantially on the axis of the sound-reproducing device effect a uniform angular distribution 35 and a proper vertical distribution of the sound waves generated by the device into the room or auditorium in which the apparatus is placed. The remaining portion of the casing comprises 40 a rigid, substantially anti-resonant structure lined with a sound-absorbent material. A large mass of sound-absorbent material is disposed in the end of the casing opposite the sound cavity in the form of a pyramid having as its base the end 45 of the casing and having its vertex in the corner of the casing including the vertex of the sound cavity.

In order still further to improve the fidelity of reproduction of apparatus embodying our invention the electrical transmission network supplying energy to the sound-reproducing device is compensated for resultant or residual lack of uniformity in the frequency-response characteristic 50 of the apparatus by associating therewith an 55

auxiliary network. Such a network may comprise one or more series resonant circuits connected in parallel and having natural frequencies corresponding to the peaks of the frequency-response characteristic of the device and one or more parallel resonant circuits having natural frequencies corresponding to the dips of the frequency-response characteristic.

For a better understanding of our invention, together with other and further objects thereof, reference is had to the following description, taken in connection with the accompanying drawings, and its scope will be pointed out in the appended claims.

15 Referring now to the drawings, Fig. 1 is a view in perspective of a sound-reproducing apparatus constructed in accordance with our invention; Fig. 2 is a longitudinal section of the apparatus of Fig. 1 taken along the lines 2-2 of Fig. 4; Figs. 3 and 4 are cross-sectional views of the apparatus of Fig. 1 taken along the lines 3-3 and 4-4, respectively, of Fig. 2; Fig. 5 represents certain operating characteristics of the apparatus of Figs. 1-4 inclusive, and certain corrections 20 applied thereto in accordance with our invention; while Fig. 6 is a schematic circuit diagram of a complete radio broadcast receiver, to which the sound-reproducing apparatus of our invention may suitably be applied, including a network 25 for compensating for any residual lack of uniformity in the frequency-response characteristic of our improved sound-reproducing apparatus.

Referring now more particularly to Figs. 1-4, inclusive, of the drawings, there is shown a 30 sound-reproducing apparatus embodying our invention comprising a casing or housing 10 terminating at its lower end in a sound cavity 11 which is separated from the upper portion of the casing by a partition 12. An opening 12a is provided in the partition in which or over which is mounted a sound-reproducing device or element 13 of the large-diaphragm type. By the term "large-diaphragm type" sound-reproducing device is meant a device having a relatively large 35 vibrating diaphragm, usually conical, which, because of its size, produces directly sound waves of sufficient intensity for usual purposes. Such a device is to be distinguished from the small-diaphragm type of sound-reproducing device which 40 is useful only in connection with a sound-amplifying device, such as a horn. The sound cavity 11 is open on two sides while its two rear sides terminate in the corner 11a, shaped to conform 45 to the vertex of a trihedral angle, such as the corner of a room, the intersections of the walls of such a room being indicated schematically by the lines 14 of Fig. 1. With such an arrangement the walls and floor or ceiling constitute 50 effectively an extension of the sound cavity 11 and secure the maximum effectiveness of the sound-reproducing device 13.

In order properly to direct and uniformly to 55 distribute sound waves generated by the device 13, there is disposed in the sound cavity 11 a conical deflector 15 the axis of which lies in the vertical through the vertex of the sound cavity 11 and the base of which is substantially coextensive with the base of the sound cavity 11. To 60 this end, and also for purposes described herein-after, it may be desirable to cut off the front corner of the casing 10, as indicated at 10a. The vertical angle of the conical deflector 15 is 65 not critical but is determined, among other considerations, by the height of the partition 12

above the base of the cavity 11 and, preferably, should be such as to direct the sound waves generated by the device 13 substantially to the head of a listener located in the center of the room in which the apparatus is to be utilized. This vertical angle is preferably of the order of 130°, although it may be varied within limits of about $\pm 20^\circ$ from this value. The deflector 15 serves principally to reflect the downwardly projected sound waves outwardly into the room.

10 In order to improve the vertical distribution of the sound waves, there is provided one or more additional segmental conical deflectors 16 substantially parallel to the deflector 15 and intermediate thereto and the partition 12. The deflector 18 preferably extends substantially to the center of the sound cavity 11 and/or to the center of the sound-reproducing device 13. To improve the angular distribution of the sound waves, there are also provided a plurality of vertical fins, in this instance the two fins 17 and 18, extending between the conical deflector 15 and the partition 12 and radiating outwardly from substantially the center of the sound cavity and/or center of the sound-reproducing device 13. 20 The fins 17 and 18 may terminate in a fin 19 extending to the rear corner of the sound cavity 11.

25 The conical deflectors 15 and 16 and the vertical fins 17, 18 and 19 must be of sufficient rigidity to prevent substantial mechanical vibration in 30 the audio-frequency range, and to this end they may comprise sheets of moderately heavy gauge metal, welded, soldered, or otherwise fabricated into a unitary structure.

35 The upper portion of the casing 10 above the partition 12 constitutes a closed sound-absorbing chamber to prevent interference of the sound waves generated at the rear of the diaphragm of the device 13 with the main sound waves which it is desired to utilize. This portion of the casing 40 is also preferably constructed of relatively heavy, rigid, anti-resonant walls and may include bracing structure to assist in securing this characteristic. This portion of the casing is substantially completely lined with a sound-absorbing sheet 45 material 20 which may be of any suitable type, as, for example, a fibrous sheet material commercially available as Acousti-Celotex. In addition, a screen or other sound-pervious sheet or strip 21 divides off from the upper portion of the casing 50 a pyramidal cavity the base of which constitutes the top of the casing 10 and the vertex of which lies at the rear corner of the casing; that is, in a vertical through the vertex of the sound cavity 11. This chamber 22 is filled with a sound-absorbent material such as rock wool or slag wool, and, if desired, a fabric covering may be provided 55 for the screen 21 to retain dust, dirt and small particles of the sound-absorbent material.

60 It is believed that the operation of our improved sound-reproducing apparatus will be clear from the foregoing description. In brief, the sound waves generated by the device 13 and projected downwardly into the sound cavity 11 are deflected or reflected from the conical deflector 15 outwardly into the room. The conical configuration of the deflector 15 tends to produce substantially uniform angular distribution of the sound waves. As stated above, the inclination of the deflector 15 should preferably be such as to deflect the sound waves upwardly at such an angle as to reach the head of a listener in substantially the center of a room in which the apparatus is to be utilized. This result may be se- 70 75

cured if the vertical angle of the conical deflector 15 is of the order of magnitude $130^\circ \pm 20^\circ$.

With the use of the conical deflector 15 alone, however, certain interference paths in the sound waves projected downwardly by the device 13 may be developed, due to the sudden change in direction effected thereby. The segmental deflector 16, together with the vertical fins 17, 18 and 19, tend to avoid any such interference patterns and to provide a more equal or uniform angular distribution of the sound waves, the deflector 15 being effective also to increase the uniformity of the vertical distribution of the sound waves as they leave the sound cavity 11. It has been found that the fins 17 and 18 and deflector 16 are particularly effective over a range of audio frequency of from 600 to 1200 cycles.

The portion of the casing 10 above the sound cavity 11 is effective to absorb sound waves generated by the rear of the diaphragm of the device 13, and this absorption should be effected without mechanical vibration of any of the casing structure. Such mechanical vibration is substantially avoided, as described above, by utilizing relatively rigid walls, with or without bracing, and by lining the walls with a sound-absorbent material. The resonant properties of the casing avoided by this means should be distinguished, however, from the resonant properties of the enclosed body of air. Resonance of the body of air is minimized by the pyramidal mass of sound-absorbent material 22, which renders the portion of the casing above the baffle 12 of non-uniform depth throughout its cross-sectional area, and by the beveled portion 10a of the casing. This beveling of the front corner of the casing substantially eliminates any parallel surfaces in this portion of the casing and thereby substantially eliminates the resonance effects or standing waves; facilitates high-angle reflection and aids in the better utilization of the corner space of the room.

The dimensions, both relative and absolute, of the above-described apparatus will be determined largely by the requirements of each particular type of installation, although the following relationships represent those found to be satisfactory in a particular case. The included angle between the side walls of the sound cavity is, of course, that determined by the trihedral angle constituting the corner of the room in which the apparatus is to be used, and is usually 90° . The vertical opening of the sound cavity 11 is preferably of the order of magnitude of the diameter of the diaphragm of the device 13. The total height of the housing 10 is not critical but is preferably at least 5 or 6 times the diameter of the diaphragm and should provide sufficient volume to build up the low notes generated by the device. The diaphragm of the device 13 is preferably parallel to the floor, although it may be inclined slightly thereto, the inclination of the deflectors 15 and 16 being correspondingly modified.

While the casing 10, and particularly the sound cavity 11 thereof, has been illustrated as conforming substantially to a right trihedral angle such as the corner of a room, it will be apparent that it may conform to any polyhedral angle, or, in general, to any conical shape, in case it is to be employed in connection with a room or auditorium, provided with a corner or vertex other than a trihedral angle. It will also be apparent that, while we have described our invention as embodied in an apparatus adapted to rest upon the floor of a room, the apparatus may be in-

verted with the sound cavity immediately adjacent the ceiling and the same principles of operation will govern the performance of the apparatus.

The frequency-response characteristic of the sound-reproducing apparatus described above, as determined by a microphone situated in such a way with respect to the apparatus as to simulate normal operating conditions, is shown by curve A of Fig. 5. From this curve it is seen that the fidelity of reproduction is reasonably uniform over the audible frequency range of from 70 to 6000 cycles. In this same figure, curve B represents a correction curve which, if applied to the apparatus whose characteristic is represented by the curve A, would produce absolutely uniform frequency response. The curve B is, obviously, the inverse of the curve A. Curve C, in this same figure, represents a correction curve obtainable by a frequency-selective network, to be described more particularly hereinafter, applied to the electrical transmission system to which the sound-reproducing device is connected. It is seen that this represents a very close approximation to the ideal correction curve B. The resultant of curves A and C is shown in curve D, which represents the frequency-response characteristic of a complete system embodying our invention. The average of the curve D has been moved upwardly from the other curves to avoid confusion and since it is relative, and not absolute, values of the response which are important. It is seen that the curve D does not depart from its average value more than about ± 3 decibels.

An electrical transmission system by means of which the characteristics of Fig. 5 may be obtained is shown in Fig. 6 of the drawings, which is a schematic diagram of a complete radio broadcast receiver modified in accordance with our invention. This system includes an input circuit 30 for connection between an antenna and ground, a radio-frequency amplifier 31, an oscillator-modulator 32, an intermediate-frequency amplifier 33, and a detector 34, all coupled in cascade. The output of the detector 34 is fed to an audio-frequency amplifier including the vacuum tubes 35 and 36 connected in any conventional manner, the circuits of which form no part of our present invention. The audio-frequency amplifier is, in turn, coupled to a push-pull power amplifier including vacuum tubes 37 and 38 and associated circuit elements, also connected in a conventional manner, which, in turn, are connected to sound-reproducing device 39, which is of the type illustrated in, and described in connection with, Figs. 1-4 inclusive.

In order to modify the frequency-response characteristics of the above system to produce the correction represented by the curve C of Fig. 5, a frequency-selective network 40, represented by the dotted outline, is included in the cathode circuit of the vacuum tube 35. This network comprises a parallel resonant circuit consisting of an inductance 41 and a condenser 42, shunted by a resistor 43, connected in series with a second parallel resonant circuit consisting of an inductance 44 and a condenser 45. Connected in parallel with the two serially connected parallel resonant circuits just described, through a blocking condenser 46, are the pairs of series resonant circuits comprising inductances 47, 49, 51 and 53 and condensers 48, 50, 52 and 54, respectively. Further, there is connected in parallel with the voice coil of the sound-reproducing device 39 a frequency-selective network 55, represented in

dotted outline, comprising series resonant inductance 56 and condenser 57.

It will be understood that the impedance constants of the several elements of the above-described frequency-selective networks will be dependent entirely upon the particular frequency-response characteristic of the sound-reproducing apparatus, per se. By way of example only, as illustrative of a frequency-selective network for producing the correction curve C of Fig. 5, the frequency-selective networks may have the following values:

Inductance 41	.12	henries
Inductance 44	.75	henries
Inductance 47	.17	henries
Inductance 49	.58	henries
Inductance 51	.5	henries
Inductance 53	.15	henries
Inductance 56	.88	microhenries
Condenser 42	.027	microfarads
Condenser 45	.15	microfarads
Condenser 46	.01	microfarads
Condenser 48	.5	microfarads
Condenser 50	.07	microfarads
Condenser 52	.007	microfarads
Condenser 54	.006	microfarads
Condenser 57	.3	microfarads
Resistor 43	3000	ohms.

As indicated in the drawings, the parallel resonant circuit 41, 42 produces the dip in curve C at 2800 cycles; the parallel resonant circuit 44, 45 produces the dip at 150 cycles; the series resonant circuit 56, 57 in the circuit of the sound-reproducing device produces a desired dip at 10,000 cycles. On the other hand, the series resonant circuit 47, 48 produces the peak at 55 cycles; the circuit 49, 50 produces the peak at 250 cycles; the circuit 51, 52 produces the peak at 850 cycles; the circuit 53, 54 produces the peak at 1700 cycles; and the output circuit including the reactor 56 and condenser 57 produces the peak at 5500 cycles.

The circuit constants for procuring the correction curve C may be determined empirically or computed in any of several well known manners. From the foregoing description it is apparent that, in accordance with our invention, there is provided a sound-reproducing apparatus having a nearly uniform frequency-response characteristic, together with a method of, and apparatus for, compensating for any residual non-uniformity in the frequency-response characteristic within any desired limits, whereby the deviation of the frequency-response curve from its average value may be maintained within any assigned error, by proper design of the frequency-selective network.

While we have described what we at present consider the preferred embodiment of our invention, it will be obvious to those skilled in the art that various changes and modifications may be made therein without departing from our invention, and we, therefore, aim in the appended claims to cover all such changes and modifications as fall within the true spirit and scope of our invention.

What is claimed is:

1. A high-fidelity sound-reproducing apparatus comprising a casing including a sound cavity shaped to conform substantially to the vertex of a trihedral angle, as a corner of a room, a large-diaphragm type sound-reproducing device disposed to radiate sound waves into said cavity at a point displaced from said vertex, and means

for directing the sound waves radiated by said device outwardly from said vertex with a substantially uniform angular distribution.

2. A high-fidelity sound-reproducing apparatus comprising a casing including a sound cavity shaped to conform substantially to the vertex of a trihedral angle, as a corner of a room, a large-diaphragm type sound-reproducing device disposed to radiate sound waves approximately vertically into said cavity, and means for directing outwardly and distributing uniformly the sound waves radiated by said device.

3. A high-fidelity sound-reproducing apparatus comprising a casing including a sound cavity shaped to conform substantially to the vertex of a trihedral angle, as a corner of a room, a large-diaphragm type sound-reproducing device disposed to radiate sound waves approximately vertically into said cavity, and a conical deflector positioned below said device and effective to direct and distribute sound waves radiated by said device outwardly from said vertex.

4. A high-fidelity sound-reproducing apparatus comprising a casing including a sound cavity shaped to conform substantially to the vertex of a trihedral angle, as a corner of a room, a large-diaphragm type sound-reproducing device disposed to radiate sound waves approximately vertically into said cavity, and rigid conical deflecting means positioned below said device and effective to direct and distribute sound waves radiated by said device outwardly from said vertex.

5. A high-fidelity sound-reproducing apparatus comprising a casing including a sound cavity shaped to conform substantially to the vertex of a trihedral angle, as a corner of a room, a large-diaphragm type sound-reproducing device disposed to radiate sound waves approximately vertically into said cavity, and a rigid conical deflector having its axis lying in a vertical intersecting said vertex and substantially coextensive with said cavity, said deflector being effective to direct and distribute outwardly from said vertex the sound waves radiated by said device.

6. A high-fidelity sound-reproducing apparatus comprising a casing including a sound cavity shaped to conform substantially to the vertex of a trihedral angle, as a corner of a room, a large-diaphragm type sound-reproducing device disposed to radiate sound waves approximately vertically into said cavity, and a rigid conical deflector having a vertical angle of the order of 130° and disposed with its axis lying in a vertical intersecting said vertex, said deflector extending substantially to the periphery of the bottom of said cavity and being effective to direct and distribute outwardly from said vertex the sound waves radiated by said device.

7. A high-fidelity sound-reproducing apparatus comprising a casing including a sound cavity shaped to conform substantially to the vertex of a trihedral angle, as a corner of a room, a large-diaphragm type sound-reproducing device disposed to radiate sound waves approximately vertically into said cavity, and a rigid conical deflector having a vertical angle of from 110° to 150° and disposed with its axis lying in a vertical intersecting said vertex, said deflector being effective to direct and distribute outwardly from said vertex the sound waves radiated by said device.

8. A high-fidelity sound-reproducing apparatus comprising a casing including a sound cavity shaped to conform substantially to the vertex of a trihedral angle, as a corner of a room, a large-

diaphragm type sound-reproducing device disposed to radiate sound waves approximately vertically into said cavity, a conical deflector positioned below said device and effective to direct outwardly from said vertex sound waves radiated by said device, and additional means for effecting uniform angular distribution of said deflected waves.

9. A high-fidelity sound-reproducing apparatus comprising a casing including a sound cavity shaped to conform substantially to the vertex of a trihedral angle, as a corner of a room, a large-diaphragm type sound-reproducing device disposed to radiate sound waves approximately vertically into said cavity, a conical deflector positioned below said device and effective to direct outwardly from said vertex sound waves radiated by said device, and a plurality of fins radiating from the interior of said cavity effecting a uniform angular distribution of said deflected waves.

10. A high-fidelity sound-reproducing apparatus comprising a casing including a sound cavity shaped to conform substantially to the vertex of a trihedral angle, as a corner of a room, a large-diaphragm type sound-reproducing device disposed to radiate sound waves approximately vertically into said cavity, a conical deflector positioned below said device and effective to direct outwardly from said vertex sound waves radiated by said device, and a second segmental conical deflector positioned above and substantially parallel to said first-named conical deflector, and a plurality of vertical fins radiating from the interior of said cavity to the periphery thereof, said segmental deflector and said fins being effective to secure uniform angular distribution of said deflected waves.

11. A high-fidelity sound-reproducing apparatus comprising a casing including a sound cavity shaped to conform substantially to the vertex of a trihedral angle, as a corner of a room, a large-diaphragm type sound-reproducing device disposed to radiate sound waves approximately vertically into said cavity, a conical deflector positioned below said device with its axis lying in a vertical through said vertex and effective to direct outwardly from said vertex sound waves radiated by said device, and means for effecting a substantially uniform angular and vertical distribution of said deflected waves comprising a unitary vane-like structure disposed above said deflector and including a segmental conical deflector parallel to said first-named deflector and a plurality of vertical fins, said segmental deflector and said fins radiating substantially from the axis of said diaphragm to the periphery of said cavity.

12. A high-fidelity sound-reproducing apparatus comprising a casing including a sound cavity shaped to conform substantially to the vertex of a trihedral angle, as a corner of a room, a horizontal partition defining the upper boundary of said cavity, a large-diaphragm type sound-reproducing device disposed in an opening in said partition and radiating sound waves vertically into said cavity, and means for directing outwardly and distributing uniformly the sound waves radiated by said device.

13. A high-fidelity sound-reproducing apparatus comprising a casing including a sound cavity shaped to conform substantially to the vertex of a trihedral angle, as a corner of a room, a horizontal partition defining the upper boundary of said cavity, a large-diaphragm type sound-reproducing device disposed in an opening in said partition and radiating sound waves vertically into said cavity, and means for directing outwardly from said vertex sound waves radiated by said device.

into said cavity, the vertical depth of said cavity being of the order of the diameter of said diaphragm, and means for directing outwardly and distributing uniformly the sound waves radiated by said device.

14. A high-fidelity sound-reproducing apparatus comprising a casing terminating in a sound cavity shaped to conform substantially to the vertex of a trihedral angle, as a corner of a room, a partition separating said cavity from the rest of said casing, a large-diaphragm type sound-reproducing device disposed in an opening in said partition to radiate sound waves substantially vertically into said cavity, means for directing the sound waves radiated by said device outwardly from said vertex, and means for rendering the casing above said partition substantially non-resonant.

15. A high-fidelity sound-reproducing apparatus comprising a casing terminating in a sound cavity shaped to conform substantially to the vertex of a trihedral angle, as a corner of a room, a partition separating said cavity from the rest of said casing, a large-diaphragm type sound-reproducing device disposed in an opening in said partition to radiate sound waves substantially vertically into said cavity, means for directing the sound waves generated by said device outwardly from said vertex, and means for rendering the casing above said partition substantially non-resonant, comprising a lining of sound-absorbent material and a mass of sound-absorbent material at the opposite end of said casing from said cavity and formed with a surface inclined to said partition.

16. A high-fidelity sound-reproducing apparatus comprising a casing terminating in a sound cavity shaped to conform substantially to the vertex of a trihedral angle, as a corner of a room, a partition separating said cavity from the rest of said casing, a large-diaphragm type sound-reproducing device disposed in an opening in said partition to radiate sound waves substantially vertically into said cavity, means for directing the sound waves radiated by said device outwardly from said vertex, and means for rendering the casing above said partition substantially anti-resonant, comprising a lining of sound-absorbent material and a mass of sound-absorbent material disposed to form a pyramid having as its base the end of said casing opposite said cavity and having its vertex at the corner of said casing including the vertex of said cavity.

17. A high-fidelity sound-reproducing apparatus comprising a casing constructed with sufficient rigidity as to be substantially anti-resonant and terminating in a sound cavity shaped to conform substantially to the vertex of a trihedral angle, as a corner of a room, a horizontal partition separating said cavity from the rest of said casing, a lining of sound-absorbent material for the last-mentioned portion of said casing, a sound-previous screen dividing a pyramidal chamber out of said casing having as its base the end of said casing opposite from said cavity, a mass of sound-absorbent material filling said chamber, a large-diaphragm type sound-reproducing device disposed in an opening in said partition and radiating sound waves substantially vertically into said cavity, and means for directing outwardly from said vertex sound waves radiated by said device.
